FLEXIBLE DRIVE COUPLING

Raymond A. Brandoli, Agawam, Mass., assignor to Worthington Corporation, Harrison, N.J., a corporation of Delaware

Filed Jan. 31, 1964, Ser. No. 78,455

Term of patent 14 years

(Cl. D55—1)

FIG. 1

FIG. 2

The broken line showing of shaft ends in FIGURE 1 is for illustrative purposes only.

I claim:

The ornamental design for a flexible drive coupling, as shown and described.
